FEELER TIP FOR WEFT REPLENISHING
LOOMSOscar V. Payne, Worcester, Mass., assignor to
Crompton & Knowles Loom Works, Worcester,
Mass., a corporation of Massachusetts

Application April 4, 1932, Serial No. 603,164

3 Claims. (Cl. 139—287)

This invention relates to improvements in feeler tips preferably for side slipping weft detectors for looms and it is the general object of the invention to provide a tip capable of withstanding repeated blows of hard yarns without appreciable wear yet operating without causing abrasion or fraying of such yarns.

When detecting hard fine wefts, such as silk, it is desirable to provide the feeler tip which can be struck a great number of blows by the same yarn surface without substantial alteration of the detecting surface through wear. It is an important object of my present invention to form a feeler tip of laminated wood the sheets of which are impregnated with a hardening agent, such as a phenolic condensation product. The sheets of wood are preferably so disposed that the end grain strikes the weft. A detector made of this material shows practically no wear after several months use and does not abrade the yarn.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a plan view of my weft detector, with adjacent portions of the lay and shuttle,

Fig. 2 is a vertical section on line 2—2 of Fig. 1 on an enlarged scale,

Fig. 3 is an enlarged plan view of a feeler tip grained to indicate the wood structure thereof,

Fig. 4 is a vertical section on line 4—4 of Fig. 3, and

Fig. 5 is a diagrammatic view representing the manner in which the tip may be made.

Referring to Fig. 1, I have indicated a lay 10 having a shuttle S supplied with a bobbin B having a wound mass of weft W. The detector D may be mounted on a fixed platform 11 supported on the loom frame and has a rearwardly projecting yielding diagonally offset arm 12. The detector, except the tip, may be of the type set forth in my prior Patent No. 1,738,198.

In carrying my present invention into effect, I preferably make the feeler tip of a laminated wood structure, fabricated according to the showing of Fig. 5. A series of thin strips of wood 20 are alternated with layers 21 of a phenolic condensation product in the form of a powder, after which the strips and the powder are subjected to considerable pressure and temperature. This treatment causes the condensation product to penetrate adjacent surfaces of the strips, and in effect produces a solid body.

I prefer to have the grain of the several sheets run in the same general direction, although cer-

tain features of my invention do not require this particular arrangement of wood. The tip is then shaped as suggested in the drawing and cut to form the weft engaging teeth 22. The latter may, though not necessarily, extend in a direction transversely of the planes of the wooden sheets, and the tip is preferably so formed that the surface which strikes the yarn is formed of end grained wood.

By making the sheets sufficiently thin it is 10 possible to cause the condensation product to penetrate a sufficient depth so that practically all of the wood is impregnated. While several kinds of wood are acceptable, yet I prefer to use either ash or white wood, since these woods 15 can be formed as thin sheets and respond to the treatment described.

From the foregoing it will be seen that I have provided a simple form of feeler tip which is found in practice to be very hard so as to resist 20 wear when detecting against hard yarns, but is sufficiently smooth and uniform in its texture to prevent abrasion of the wefts. It will also be seen that the laminations may be so arranged as to present end grain to the weft, a structural 25 condition tending to hold the detector against sliding along a very hard wound mass of weft. Experience shows that no hesitancy exists on the part of the detector in slipping along a bare bobbin. Although described in connection with a 30 side slip feeler, yet my invention is not limited to such use.

Having thus described my invention it will be seen that changes and modifications may be made therein by those skilled in the art without departing from the spirit and scope of the invention and I do not wish to be limited to the details herein disclosed, but what I claim is:

1. A feeler tip formed of a series of wood sheets bound together by and impregnated with a 40 phenolic condensation compound and having the grain of all the sheets running in substantially the same direction and having the yarn engaging teeth formed of end grain.

2. A feeler tip formed of a series of flat strips 45 of wood parallel to the length of the surface to be detected and having their grain running in a direction parallel to the direction of movement of the weft presented to the tip, said sheets of wood being bound together and impregnated 50 with a phenolic condensation compound.

3. A feeler tip formed of a series of sheets of wood bound together with their grain running in substantially the same direction and having teeth 55 cut across end grain of the wood to present a detecting surface.

OSCAR V. PAYNE.
